UNITED STATES PATENT OFFICE.

HAMILTON J. SMITH, OF RICHMOND, VIRGINIA.

STREET INDICATOR.

Application filed March 25, 1924. Serial No. 701,748.

To all whom it may concern:

Be it known that I, HAMILTON J. SMITH, a citizen of the United States, residing at Richmond, in the county of Henrico and 5 State of Virginia, have invented certain new and useful Improvements in Street Indicators; and I do hereby declare the following to be a full, clear, and exact description of the invention, such as will enable others 10 skilled in the art to which it appertains to make and use the same.

My invention relates to new and useful improvements in street indicators, and has for its object to provide a device of this kind, 15 which is simple in construction, accurate in operation and which can be manufactured at a reduced cost.

It is a well known fact, that at present passengers on a street car, many of whom 20 are often strangers, do not know when they have reached the street or station at which they desire to leave the car. They will frequently ask a conductor to inform them when they arrive at a certain street, and the 25 conductor will sometimes remember, but more often he is thinking of something else until it is too late, or he will not know the streets well enough himself.

This is very inconvenient to the passengers, especially when they are in a hurry 30 and will have to walk several blocks to reach the desired destination.

With my improved device this difficulty is overcome. The conductor simply turns a 35 handle or lever at each corner and sounds an alarm to inform all of the passengers just where the car is.

With the above and other objects in view, which will appear as the description proceeds, my invention consists in the novel features herein set forth, illustrated in the accompanying drawing and more particularly 40 pointed out in the appended claims.

In referring to the drawing, numerals of 45 like character designate similar parts throughout the several views.

Fig. 1 is a front view of my improved street indicator.

Fig. 2 is a sectional view taken on line 50 2—2 of Fig. 1.

Fig. 3 is a section taken on line 3—3 of Fig. 2 showing the device with the front removed, and

Fig. 4 is a side view of Fig. 1, showing the 55 handle and ratchet mechanism.

In the drawings, 1 designates the box proper or casing, which may be constructed of wood, metal, a combination of the two, or any other suitable material. This casing includes two sections, 2 and 3, the former being the main portion in which the mechanism is mounted, and the latter being a sort of receptacle for the ends of the indicating strip as will be described later.

Between the side walls of the portion 2 of the casing are rotatably mounted a plurality of rollers 4, 5 and 6, the rollers 4 and 6 being free and frictionally driven, while the roller 5 is operated by a ratchet 7, mounted in connection with said roller outside of the casing 1. Between the ratchet 7 and the casing 1, pivoted on the bearing of the roller 5, is a lever 8, having secured to one end thereof a handle 9, which actuates the ratchet 7 in either direction through the medium of a reversible pawl 10. The pawl 10 is rotatably mounted on the lever 8, and consists of a cam portion 11, which is engaged by a spring 12, and a ratchet engaging portion 13.

On the rollers 5 and 6, I provide a belt 14 composed of rubber or any suitable material, for creating friction, and which will serve as a support for the indicating strip 15. This strip 15 is free at both ends as shown in Fig. 3, and is composed of canvas or any other suitable material, having the names of the streets or stations printed or stenciled thereon. The strip is carried and gripped between the rollers 4 and 5, with its ends extending downwardly into the receptacle portion 3 of the casing 1.

In front of the rollers and strip 15, I provide a plate 16, slidably mounted in the casing 1, and having therein a window 17, through which can be seen the names of the 95 streets on the strip 15.

The device is detachable and provided with hooks 18 to enable it to be fastened in either end of the car.

The operation of my invention is obvious. The indicator is hooked up in the end of the car where the conductor can easily reach it and as the car passes each corner, the conductor sounds an alarm of any kind, and pulls the lever 8, which causes the pawl 10 to engage the ratchet 7 and turn the same a predetermined distance. This in turn actuates the roller 5 and with it the strip 15, which is fed between the rollers 4 and 5, and which is supported by the rubber belt 110

14 in such a manner that each of the street names respectively will register with the window 17.

When the end of the route is reached, the 5 indicator is transferred to the opposite end of the car, and the pawl is reversed as shown in dotted lines in Fig. 4, and the operation is repeated.

This device may be used in buses, taxi 10 cabs and local trains as well as street cars.

From the foregoing, it is believed that my invention may be clearly understood, without further description, it being borne in mind that numerous changes may be 15 made in the details of construction, without departing from the spirit of the invention as disclosed in the following claims.

What I claim and desire to secure by Letters Patent is:—

20 1. A street indicator for use in vehicles, including a casing, a flexible indicating strip having the names of streets thereon,

mounted in said casing, a plurality of rollers also mounted in said casing, two of said rollers being provided with a belt to support said strip, said strip being fed between the other of said rollers and the last named rollers, past a window and into and out of a receptacle, and means for operating said rollers.

2. A street indicator as claimed in claim 1, wherein said strip is free at both ends, each end extending into the said receptacle.

3. A street indicator as claimed in claim 1, wherein the means for actuating said rollers consists of a pawl and ratchet construction.

4. A street indicator as claimed in claim 1, wherein the means for actuating said rollers consists of a reversible pawl and ratchet construction.

In testimony whereof I affix my signature

HAMILTON J. SMITH.
